CLAIM

The ornamental design for an electronic display with graphical user interface for an HVAC scrubber unit, as shown and described.

DESCRIPTION

The FIGURE illustrates a front view of an electronic display with graphical user interface for an HVAC scrubber unit, showing the new design.

The outer broken line rectangle showing the electronic display, and all other broken lines showing portions of the

(Continued)

graphical user interface, illustrate portions of the article. None of the aforementioned broken lines form part of the claimed design.
